(57) **CLAIM**

The ornamental design for an ergonomic harness, as shown and described.

DESCRIPTION

FIG. 1 is a front perspective view of an ergonomic harness showing our new design in a fastened configuration;

FIG. 2 is a front elevation view of the ergonomic harness illustrated in FIG. 1;

FIG. 3 is a rear elevation view of the ergonomic harness illustrated in FIG. 1;

FIG. 4 is a right side elevation view of the ergonomic harness illustrated in FIG. 1;

FIG. 5 is a left side elevation view of the ergonomic harness illustrated in FIG. 1;

FIG. 6 is a top plan view of the ergonomic harness illustrated in FIG. 1;

FIG. 7 is a bottom plan view of the ergonomic harness illustrated in FIG. 1; and,

FIG. 8 is a top plan view of the ergonomic harness of FIG. 1 in an unfastened configuration.

The broken lines shown in the drawings depict lines of stitching on the ergonomic harness that form no part of the claimed design.

1 Claim, 8 Drawing Sheets
